UNITED STATES PATENT OFFICE.

PAUL CHRISTLEIN, OF NUERMBERG, AND GUSTAV MÖLLER, OF CHARLOTTENBURG, BERLIN, GERMANY.

CONDENSING APPARATUS.

1,166,324.

Specification of Letters Patent. Patented Dec. 28, 1915.

Application filed November 14, 1913. Serial No. 801,021.

To all whom it may concern:

Be it known that we, PAUL CHRISTLEIN and GUSTAV MÖLLER, residing in Nuremberg, Bavaria, and Charlottenburg, Berlin, Germany, respectively, have invented certain new and useful Improvements in Condensing Apparatus, of which the following is a specification.

The driving of the various machines and pumps such as are necessary for the working of condensation apparatus by means of one single driving engine is rendered extremely difficult and cumbersome owing to these machines requiring different numbers of revolutions. In centrifugal pumps for cooling water which are called upon to raise a very large volume to the small head of eight to sixteen meters, this number of revolutions is at about 300 to 1000 per minute; for condenser pumps particularly when they are used for the return feed of the boiler, at about 3000 to 7000 revolutions per minute; and finally, in pumps serving for the generation of pressure water for the various jet apparatus for drawing off air the rotary speed is at about 2000 to 4000 revolutions per minute. Where such pumps are to be driven by a high speed engine such as a steam turbine, efforts will be made owing to the relatively small output and in considering cheapness of manufacture and a fair efficiency to impart to them a rotary speed as high as possible, that is, hardly less than 3000 revolutions per minute. In these circumstances, therefore, a direct driving of all pumps by a single driving engine is not possible.

Hitherto the individual pumps were therefore provided with individual driving motors or particular transmissions were constructed and interposed between the individual pumps. The whole working, however, is rendered considerably simpler, particularly for condensation plants, if according to the present invention one or several of the pumps themselves are constructed to form a liquid transmission so as to enable two or several shafts having different rotary speeds to be used on which the different pumps or also other auxiliary engines are distributed at will according to their rotary speed. In this manner it is possible to drive

the whole of the pumps or auxiliary engines at most variable speeds simultaneously by means of a single driving engine.

The transmission is effected by the more rapidly running (driving) centrifugal pump delivering its medium into a slower running turbine which latter is arranged directly to drive the different other pumps located either in the same casing or in an individual housing. Such liquid transmissions are in general *per se* well known in the construction of pumps. The great advantages of their use for condensation plants, however, were hitherto not known.

Several constructional forms of a condensation plant according to this invention are shown by way of example in the accompanying drawings.

The construction shown in Figure 1 represents a cooling water pump arranged as a transmission pump. The driving engine A drives a small high pressure centrifugal pump *a* which draws in a portion of the cooling water by way of the suction pipe *s'* and raises it to a higher pressure than is necessary for the forcing of the cooling water. The excess energy is utilized for driving a blade wheel *b* (turbine) which is arranged concentrically to surround the pump *a*. The blade wheel *b* is therefore driven at a lower rotary speed than that of the high pressure pump *a*. After the water has delivered the excess energy to the blade wheel *b* it passes into the pressure chamber *c* in which the pressure corresponds to the required head of the cooling water. The blade wheel *b* is rigidly connected to a low pressure centrifugal pump *d* which at a speed which is lower than that of the high pressure pump *a* draws in the main volume of the cooling water by way of the suction pipe *s''* raising it directly to the required head and forcing it into the condenser D by way of the pressure conduit *p'*. The slowly rotating shaft *e* of this low pressure pump *d* is used according to the nature of the plant simultaneously to drive a rotary air pump B or a water pump adapted to operate an ejector or jet apparatus, for sucking away air, or also further auxiliary engines. The high speed driving shaft *f* is used simultaneously to

drive a pump C for water of condensation or a return feed pump. The higher the number of revolutions which it is possible to impart to the high pressure pump and to the driving engine, the cheaper and more economical it will act in the working. Now in order to enable the head and also the rotary speed of the high pressure pump which is directly driven to be still further increased, the arrangement may be such that the liquid medium of the high pressure pump is employed not only for speed transmission but also for sucking away and for forcing the air of the condenser to the atmosphere. In this case further additional energy must be imparted to the medium and this is effected by raising the number of revolutions of the high pressure pump.

Fig. 2 illustrates an arrangement of the latter kind. The driving engine A again drives a high pressure centrifugal pump *a* which raises the water to a head sufficient for driving the slowly rotating blade wheel *b* and for operating an ejector *L* to remove air from the condenser D. Therefore from the blade wheel *b* the water is supplied through the pressure chamber *c* and by way of the pressure conduit *p*² to the jet device *L* which removes air from the condenser. After passing through the ejector *L* the water may either mix with the cooling water or be discharged separately from the latter. The low pressure pump *d* is coupled with the blade wheel *b*, as in the first example, and raises the main volume of the cooling water directly through the suction conduits *s*² and forces it by way of the pressure pipe *p'*, into the condenser D at the required pressure. If it is desired to avoid the losses in the chamber *c* due to the translation of velocity into pressure the velocity of the medium at the outlet of the blade wheel *b* may be used directly for sucking away air and for raising purposes by appropriately shaping the chamber *c* for the passage of air and connecting it with the air space of the condenser. In order to protect the individual parts of the high pressure pump *a*, the blade wheel *b* and the air removing apparatus from mechanically or chemically impure water it will be advisable to cause the high pressure pump *a* to withdraw from and discharge into a tank filled with pure water so that the same liquid may be used continuously. This has the further advantage of enabling other liquids than water to be used for power transmitting and air removing purposes such as oil or mercury which owing to their low internal friction or great specific weight promise a better degree of efficiency or a more compact construction. Moreover, such a tank may be placed at a sufficiently high level to insure a starting of the pump in any circumstances and to be independent of

the fluctuating suction level of the cooling water source.

Fig. 3 represents an arrangement of the latter kind. The high pressure pump *a* sucks liquid by way of the pipe *s* from the collecting tank E and forces it into the blade wheel *b*. As in the previous case, the liquid is forced through the pipe *p*² into the air evacuating apparatus *L* which draws air from the condenser D through the pipe. After passing the air suction apparatus the liquid returns to the collecting tank E by way of the pipe *h*. In its passage it may be conducted through the condenser for cooling purposes or alternatively it may itself be cooled at some suitable place if this should be necessary. The blade wheel *b* drives, as in the previous examples, the cooling water pump *d* and the necessary pumps and auxiliary engines are distributed at will on the shafts running at different speeds. The centrifugal wheels as well as the blade wheels may obviously be constructed in various shapes according to the purpose of the plant and according as this is preferable in the construction of pumps or turbines. Moreover, the pumps or turbines for the purpose of attaining a higher transmission ratio may be multi-staged or two or more transmissions may be arranged in series so that three or more shafts rotating at different speeds would be used. Further, the whole aggregate may be built into one casing in order to attain greater simplicity.

What we claim and desire to secure by Letters Patent:—

1. A condensing plant comprising in combination a main condenser, a single high speed driving engine, a high pressure centrifugal pump driven by said engine, a turbine driven by the fluid discharged from said centrifugal pump and running at a lower speed than said pump, a secondary pump mechanically connected with said turbine and an ejector for withdrawing air from the condenser, said ejector being actuated by the fluid after it has passed through said turbine.

2. A condensing plant comprising in combination a main condenser, a single high speed driving engine, a high pressure centrifugal pump driven by said engine, a turbine driven at a lower speed by the fluid discharged from said centrifugal pump, a secondary pump mechanically connected with said turbine, and an ejector for withdrawing air from the condenser, said ejector being operated by fluid from said pressure chamber after it has been discharged from said turbine.

3. In a condensing apparatus comprising in combination, a main condenser, a collecting tank, a single driving engine, a high pressure centrifugal pump driven by said

engine, for raising a portion of the cooling fluid from said collecting tank, a turbine driven by the discharge from said centrifugal pump and discharging directly into a pressure chamber, a secondary pump mechanically connected to said turbine for supplying cooling fluid directly to the condenser, an ejector for withdrawing air from the condenser, said ejector being actuated by fluid from the turbine, and a return pipe from said ejector to said collecting tank.

In testimony whereof we have affixed our signatures in presence of two witnesses.
